UNITED STATES PATENT OFFICE.

SVEN PETER ALQUIST, OF DENISON, TEXAS, ASSIGNOR, BY DIRECT AND MESNE ASSIGNMENTS, OF NINE-TWENTIETHS TO WILLIAM L. KELLOGG, OF PARSONS, KANSAS, AND TWO-TWENTIETHS TO ALLAN S. BARROWS, OF CHICAGO, ILLINOIS.

GRAIN-DOOR.

1,260,251.

Specification of Letters Patent. Patented Mar. 19, 1918.

Application filed October 23, 1915. Serial No. 57,590.

To all whom it may concern:

Be it known that I, SVEN PETER ALQUIST, a citizen of the United States, residing at Denison, in the county of Grayson and State of Texas, have invented certain new and useful Improvements in Grain-Doors, of which the following is a specification.

My invention relates to a grain door for a railway car, and the principal object of the invention is to provide a grain door structure which may be made entirely or very largely of sheet metal pressed to the desired configuration, and which will be strong, rigid, simple and compact in construction and comparatively economical to manufacture.

The invention consists, in part, of certain constructions for providing the main grain door with a relief or sub-door which can be readily opened to relieve the pressure against the main door when the grain is to be unloaded, and which will close tightly against the main door to prevent any possible leakage of the grain at such times as the car is used as a grain carrier. The invention contemplates, preferably, having the main door slide back and forth across the door opening, in which case the construction is such that the sub-door will not hinder the sliding movement of the main door. The main door, moreover, is located so that it and its attachments are in a protected position, when the door is slid back from the door opening, while the car, for example, is used for carrying ordinary freight, so that these parts are not liable to injury from shifting of the cargo or like causes.

The invention consists of such other new and improved constructions, arrangements, and devices relating to grain doors for railway box cars as will be hereinafter described and claimed.

The invention is illustrated in a preferred embodiment in the accompanying drawings, wherein—

Figure 1 is a fragmentary side elevation of the superstructure of a railway box car provided with the usual outside sliding door which is illustrated as pushed back from the door opening so as to show the grain door of my invention in its operative position.

Fig. 2 is a sectional plan on line 2—2 of Fig. 1 but on a larger scale than Fig. 1,

Fig. 3 is a similar vertical section on line 3—3 of Fig. 1.

Fig. 4 is a fragmentary view, in perspective, illustrating the device for locking the sub-door to the main door; and

Fig. 5 is a similar view of the guiding and retaining strip arranged at the threshold of the door opening to support and guide the grain door.

Like characters of reference designate like parts in the several figures of the drawings.

Referring to the drawings, 10 indicates the side sheathing of a railway box car, 11 the door opening in the side of the car, 12, 13 the door posts, 14 the side sill and 15 the outside sliding door which may be supported in any desired manner. The main grain door 16 consists preferably of a single sheet of metal pressed to a dished configuration with flat marginal flanges 17, 18, 19, 20. The lower flange 18 rests and is slidable upon a metal strip 21 (Fig. 5) which extends across the door opening and backwardly into the car on one side thereof. The portion within the side sheathing is preferably formed with an upstanding guide flange 22. 23, 24 are threshold plates providing between them a channel for the lower flange 18 of the door. The flange 18 is notched at one corner as shown at 25, and the strip 21 is formed or provided with projections 26, 26. When the door is in position across the door opening, the projection 26 is engaged with the notch 25, this engagement operating to hold the door in proper place against the door posts. When the door is opened the notch 25 comes into engagement with the projection 26 by means of which the door is held in its open position against accidental displacement from vibration or other causes. The upper marginal flange 17 enters a channel shaped guide 27 attached to the inside of the wall of the car. When the door is in its operative position the flanges 19 and 20 bear against the door posts 12, 13 respectively.

The main door 16 is formed, preferably at one lower corner, with an opening 28 and the metal is pressed out around this opening to form an outstanding rib or corrugation 29. The opening 28 is closed by means of a sub-door 30 formed of sheet metal and

pressed with a marginal corrugation 31 adapted to fit over the corrugation 29 on the main door. The door 30 is preferably hinged to the main door by hinges 32, the attachment being made to the concave side of the main door. 33 is a preferably wedge-shaped locking member on the inside of the sub-door having a shank 34 which passes through the sub-door, and through a reinforcing plate 35 riveted thereto, and which is squared at its outer end for a handle 36; the locking member engages the corrugated edge of the main door (see Fig. 4) with a wedging engagement which forces the sub-door against the main door. By the arrangements just described the possibility of the leakage of grain between the main door and the sub-door is effectively prevented, even though, as will necessarily be the case, the pressure against the sub-door is very considerable. By manipulation of the handle 36 the sub-door is readily unlocked so that it will swing out to relieve the pressure of grain against the main door sufficiently to allow the latter to be slid back in its guides. It will be observed that the sub-door, being located within the dished portion of the main door, does not interfere in any way with the sliding movement of the main door. Moreover, the sub-door and its attachments are protected against injury when the grain door structure is pushed away from the door opening, as will be the case at such times as the car is being used for carrying ordinary freight. The dished construction of the main door gives it considerable capacity for withstanding the thrusts to which it may be subjected, due to shifting of the cargo when the car is used for carrying package freight.

Preferably the main door is further strengthened by forming it with a plurality of corrugations 37 which are pressed out into the hollow or dished portion of the door. The rear lower corner of the main door is preferably beveled off as indicated at 38, so that when the door is moved to its open position it will easily ride over the projection 26^a on the strip 21. Preferably the forward lower corner of the door is provided with a notch 25^a in which the projection 26 seats when the door is open so that the edges of the door will rest squarely on the strip 21.

My invention has been shown and described in what is considered as its most desirable embodiment, but it is realized that modifications might be made without departing from the principles of the invention. Therefore I do not wish to be under-

stood as limiting the invention to the particular constructions, arrangements and devices particularly described and shown, except so far as the claims are specifically so limited.

65

I claim:

1. A sheet metal grain door for a railway car, comprising a sheet of metal pressed into a dished configuration with marginal flanges adapted to bear against the door frame of a car, said door being formed in the lower portion thereof with an opening and with a pressed out corrugation surrounding said opening, a sheet metal sub-door hinged to the first-named door on the concave side thereof and formed with a marginal corrugation which interlocks with the aforementioned corrugation, and fastening means for holding said sub-door in closed position.

70

2. A railway car formed with a door opening and provided at one side of said door opening within the car with guiding means for a door, in combination with a sheet metal grain door pressed to a dished configuration with the dished portion projecting inwardly into the car and with the marginal portions thereof forming flanges adapted to enter said guiding means; said door being formed with an opening and with an outstanding corrugation surrounding said opening, a sub-door hinged to said main door within the dished portion thereof provided with a marginal corrugation which interlocks with the corrugation on the main door, and fastening means for holding said sub-door in closed position.

85

3. A railway car formed with a door opening and provided at one side of said door opening within the car with guiding means for a door, in combination with a sheet metal grain door pressed to a dished configuration with the dished portion projecting inwardly into the car and with the marginal portions thereof forming flanges adapted to enter said guiding means; said door being formed with an opening and with an outstanding corrugation surrounding said opening, a sub-door hinged to said main door within the dished portion thereof provided with a marginal corrugation which interlocks with the corrugation on the main door, and a revoluble locking element on the sub-door adapted to have a wedging engagement with the corrugated edge of the main door and provided at its outer end with a handle which is located within the concavity of the main door.
